LUBRICANT DISPENSING STRUCTURE

John F. Werder, Lakewood, Ohio, assignor of one-half to Edmund Rogers, South Euclid, Ohio

Application December 1, 1933, Serial No. 700,624

9 Claims. (Cl. 137—21)

This invention relates to an improved form of supporting base for a fluid container and a valve structure for dispensing the contents thereof.

The present invention is especially adapted for use in dispensing a lubricant charged with inert gas, as for instance carbon dioxide, but its use is not limited to this particular liquid.

One object of the present invention is to devise a compact and conveniently arranged combination of supporting base and valve structure to which the fluid container may be attached for discharging purposes.

It is also the object of my invention to devise a valve structure in which the parts are so formed and assembled that it is proof against leaking at any point thereof.

Other objects will appear from the following description and claims when considered together with the accompanying drawing.

Fig. 1 is a vertical sectional view of my improved device;

Fig. 2 is an enlarged view of a portion of the valve structure as shown in Fig. 1; and

Figs. 3 and 4 are taken on lines 3—3 and 4—4, respectively, of Fig. 2.

It is to be understood that the present disclosure is merely for purposes of illustration and that various modifications may be made without departing from the spirit of the present invention as herein set forth and claimed.

The supporting base has the legs 1, three or more in number, which are slightly inclined and within the central part of which there is arranged the valve structure.

The valve structure, considered as a whole, is of an inverted T-shape as will be seen from the drawing (Fig. 1), and comprises a one-piece L-shaped member to which another member is attached.

The L-shaped member has the vertically disposed tubular arm 2 and the horizontally disposed tubular arm 3. The L-shaped member is either formed integrally with the supporting base or may be suitably secured thereto.

The arm 2 is screw-threaded upon the outside thereof and is adapted to receive the screw-threaded nozzle 4 which is affixed to the container 5. The inner end of the nozzle 4 has the flange 6 surrounding the opening 7 which is closed by a frangible seal prior to the attachment of the container to the valve structure. This seal is adapted to be broken by the projecting end portion 8 of the member which is adapted to be engaged between the upper end of the arm 2 and the flange 6. This member has a portion 9 extending within

the passage of the arm 2 and has a shoulder for engagement with the upper end of the arm 2, while its conical surface 10 is adapted for sealing engagement with the outer annular edge of the flange 6 about the opening 7. Either or both of these interengaging members are formed of semi-soft metal so as to permit an effective sealing seat to be formed between the edge of the flange 6 and the conical surface 10 when the parts are brought into engagement.

The member which is employed to break the seal over the opening 7, has a passage 11 extending longitudinally therethrough and has also the transverse passage 12 communicating with the other passage 11, so that the broken seal disk will not prevent discharge of the contents.

The outlet arm 13 has screw-threaded engagement with the L-shaped member and extends in alignment with the arm 3. The arm 13 has a shoulder and seat engagement at the point 14 which is located upon the opposite side of the passage in the arm 2, that is, between the passages in the arms 2 and 3. The arm 13 has also a shoulder and seat engagement upon the outside of the L-shaped member, as indicated at the point 15. Either the L-shaped member or the member 13, or both of them, may be formed of semi-soft metal, and the distance between the shoulders 14 and 15 of the arm 13 may be the same as that between the corresponding seats, in which event, there will be effected sealing engagements at the two points at the same time. However, it is preferred that the distance between the shoulders 14 and 15 of the arm 13 be slightly greater than that between the corresponding seats, so that upon screwing the arm into assembly, the surfaces at 14 may first form an effective sealing engagement by virtue of the yielding nature of the metal, and then a sealing engagement may also be formed at 15 upon further screwing the arm 13 into assembly.

The inner end portion of the arm 13 is spaced from the wall of the L-shaped member and has a diametrically disposed passage 16 which in turn communicates with the longitudinally extending passage 17, the end of which affords a seat for the needle valve 18 formed on the end of valve stem 19. The valve stem 19 extends through the tubular arm 3 and has the packing 20 and is screw-threaded into the end of the arm 13, with the result that the conical surface of the valve 18 has a line contact with the annular edge about the end of passage 17. Either or both of the member 13 and the valve 18 may be formed of semi-soft metal so as to permit an effective sealing engage-

ment when the valve is turned into closed position. The spring 21, which forms part of the packing assembly, abuts at its other end against the reduced end of the discharge arm 13.

5 The space surrounding the valve 18 has communication through the passage 22 with the main passage through the outlet member 13. Thus, by means of the valve 18, the discharge of the fluid is controlled from the container to the discharge 10 tube 23 which is attached to the end of the arm 13. Upon the end of the tube 23 there may be provided any desired form of manually operable 15 valve for readily dispensing the lubricant or other fluid from the container after the valve 18 has been opened.

Upon discontinuance of use of the discharge device, the valve 18 will first be closed and the tube 23 will be permitted to drain before closing the valve on the outer end thereof. Then there 20 is precluded any danger of discharge of the material as might otherwise occur upon accidental opening of the valve on the outer end of the tube 23.

Also, the seal at the point 14 prevents the 25 lubricant or other liquid in the container from reaching the packing 20 and consequently leaking therethrough as might otherwise happen.

As indicated in the drawing, the arms 3 and 13 30 constitute what might be recognized as the head of the inverted T-form of valve structure, and the arms 3 and 13 are confined substantially 35 within the limits of the legs 1 of the supporting base.

The entire assembly may be carried by the 35 handle 24 which is mounted in the bracket 25. These brackets continue as straps 26 about the body of the spherical container 5 and are pivotally mounted upon the supporting base. The wing nut 27 is applied to the one end of the bolt 40 28 which extends through the upper ends of the brackets and through the handle so as to maintain these parts in assembly. Upon disassembly of these parts, an empty container can be removed and a full one substituted by screwing its 45 nozzle 4 onto the threaded arm 2 in the manner above referred to.

Thus, I have devised a compact form of structure which can be conveniently handled and employed and in which all points of connection in 50 the valve structure are effectively sealed against leakage. The sealing of the valve structure is especially important in the dispensing of gas-charged lubricant because of the fact that the lubricant is discharged under 55 the pressure of the gas which is liberated from the gas-charged lubricant itself upon initiation of and during the discharging operation, but this structure may be employed with other liquids as well and the following claims are not to be understood as being limited in this respect.

60 What I claim is:

1. A valve structure comprising a member having two angularly disposed tubular arms, one of said arms having means of connection to a source of supply, a valve member adjustably mounted in the other of said arms, and a separate auxiliary tubular member attached to and extending from said first member and having communication with the passage in the first-mentioned of said arms for discharge therefrom and having a valve opening and seat arranged for control engagement by said valve so as to regulate the flow from the first-mentioned of said arms to said auxiliary member, and said auxiliary member having effective sealing engagement with said

first member at a point between the passages in the first two arms of said first member so as to prevent leakage.

2. A valve structure comprising a member having two angularly disposed tubular arms, one of said arms having means of connection to a source of supply, a valve member adjustably mounted in the other of said arms, and a separate auxiliary tubular member attached to and extending from said first member and having communication with the passage in the first-mentioned of said arms for discharge therefrom and having a valve opening and seat arranged for control engagement by said valve so as to regulate the flow from the first-mentioned of said arms to said auxiliary member, at least one of said members being formed of semi-soft metal, and said auxiliary member having effective sealing engagement with said first member at a point between the passages in the first two arms of said first member so as to prevent leakage.

3. A valve structure comprising a member having two angularly disposed tubular arms, one of said arms having means of connection to a source of supply, a valve member adjustably mounted in the other of said arms, and a separate auxiliary tubular member attached to and extending from said first member and having communication with the passage in the first-mentioned of said arms for discharge therefrom and having a valve opening and seat arranged for control engagement by said valve so as to regulate the flow from the first-mentioned of said arms to said auxiliary member, and said auxiliary member having effective sealing engagement with said first member at opposite sides of said valve engagement so as to prevent escape of material from the passage in said first-mentioned arm except through said valve opening.

4. A valve structure comprising a member having two angularly disposed tubular arms, one of said arms having means of connection to a source of supply, a valve member adjustably mounted in the other of said arms, and a separate auxiliary tubular member attached to and extending from said first member and having communication with the passage in the first-mentioned of said arms for discharge therefrom and having a valve opening and seat arranged for control engagement by said valve so as to regulate the flow from the first-mentioned of said arms to said auxiliary member, at least one of said members being formed of semi-soft metal, and said auxiliary member being so constructed that it will first seat with effective sealing engagement with the said other member at the opposite side of the passage through the first-mentioned arm and will then seat with effective sealing engagement with the near side of said passage through the first-mentioned arm, so as to prevent escape of material from the passage in the first-mentioned arm except through said valve opening.

5. A valve structure comprising a member having two tubular arms disposed at substantially right angles to each other, one of said arms having means of connection to a source of supply, a separate auxiliary tubular member having screw-thread engagement in said member and extending from and in substantial alignment with the said other arm and having a valve opening for controlling communication between the passages in said first-mentioned arm and said auxiliary tubular member arm, and a valve member extending through the passage in the other arm of said member and having adjustable engage-

ment with said auxiliary member and being adapted for engagement with said valve opening, said auxiliary member being formed of semi-soft metal and being so constructed that it will first 5 seat with effective sealing engagement with said other member at the opposite side of the passage through the first-mentioned arm and will then seat with effective sealing engagement with the near side of said passage through the first-mentioned arm, so as to prevent escape of material 10 from the passage in the first-mentioned arm except through said valve opening.

6. A valve structure comprising a member having two tubular arms disposed at substantially 15 right angles to each other, one of said arms having means of connection to a source of supply, a separate auxiliary tubular member having screw thread engagement in said member and extending from and in substantial alignment with the said 20 other arm and having a valve opening for controlling communication between the passages in said first-mentioned arm and said auxiliary tubular member, said auxiliary member extending across the mouth of the passage through the first-mentioned of said arms and having shoulders engaging 25 corresponding seats provided in said member upon opposite sides of the passage through the first-mentioned of said arms, the distance between said shoulders being greater than that between the corresponding seats prior to assembly 30 of the same, said auxiliary member being formed of semi-soft metal so that it will seat first with effective sealing engagement at the opposite side of said passage and will then seat with effective 35 sealing engagement with the seat upon the near side of said passage, and a valve member extending through the passage in the other arm of said member and having adjustable engagement with said auxiliary member and being adapted for engagement with said valve opening, whereby there 40 will be prevented escape of material from the passage in the first-mentioned arm except through said valve opening.

7. In a device of the class described, the combination of a supporting base, an inverted T-shaped valve structure affixed to the base and having its laterally extending arms disposed substantially within the limitations of the base, means for removably supporting a fluid container in discharging relation upon the upwardly 45 extending arm of said inverted T-shaped valve structure, a valve member extending through one of the laterally disposed arms of said inverted

T-shaped structure, and means for attaching a discharge connection to the other laterally disposed arm thereof.

8. In a device of the class described, the combination of a supporting base, an L-shaped tubular member affixed to the base, one arm of said member extending laterally within the limitations of the base, the other arm thereof extending vertically and having means for removably supporting a fluid container in discharging relation 10 thereupon, a valve member extending coaxially in said laterally disposed arm, and a separate auxiliary tubular member attached to said L-shaped member and extending from and in alignment with said laterally disposed arm so as to form an 15 inverted T-shaped structure and having a valve opening adapted for engagement by said valve, said valve opening being positioned so as to permit flow of material from the vertically disposed arm out through said auxiliary member, and 20 means for attaching a discharge connection to said auxiliary member.

9. A valve structure comprising a member having two tubular arms disposed at substantially right angles to each other, one of said arms having means of connection to a source of supply, a separate auxiliary tubular member having screw-thread engagement in said member and extending from and in substantial alignment with the said other arm and having a valve opening 25 for controlling communication between the passages in said first-mentioned arm and said auxiliary tubular member, said auxiliary member extending across the mouth of the passage through the first-mentioned of said arms and having 30 shoulders engaging corresponding seats provided in said member upon opposite sides of the passage through the first-mentioned of said arms, the distance between said shoulders being at least 35 equal to that between the corresponding seats, said auxiliary member being formed of semi-soft metal so that it will seat with effective sealing engagement upon both sides of said passage, and a valve member extending through the passage in the other arm of said member and having adjustable engagement with said auxiliary member and being adapted for engagement with said valve opening, whereby there will be prevented 40 escape of material from the passage in the first-mentioned arm except through said valve opening.

JOHN F. WERDER.
